M. W. CLUXTON.
METAL SHEET PILING (JUNCTION UNIT).
APPLICATION FILED MAR. 28, 1908.

909,548.

Patented Jan. 12, 1909.

UNITED STATES PATENT OFFICE.

MANLEY W. CLUXTON, OF CHICAGO, ILLINOIS.

METAL SHEET-PILEING (JUNCTION UNIT).

No. 909,548.

Specification of Letters Patent.

Patented Jan. 12, 1909.

Application filed March 28, 1908. Serial No. 423,837.

To all whom it may concern:

Be it known that I, MANLEY W. CLUXTON, a citizen of the United States, and a resident of Chicago, in the county of Cook and State of Illinois, have invented certain new and useful Improvements in Metal Sheet-Piling, (Junction Unit;) and I do hereby declare that the following is a full, clear, and exact description thereof, reference being had to the accompanying drawings, and to the letters of reference marked thereon, which form a part of this specification.

This invention relates to improvements in interlocking metal sheet piling and refers more specifically to improvements designed to facilitate the joining of meeting or intersecting walls made or constructed of such piling.

The invention consists in the matters hereinafter set forth and more particularly pointed out in the appended claims.

My improvements are more specifically adapted to that form of metal sheet piling wherein a wall composed of such piling comprises alternate simple and compound sections which have interlocking connection at their margins. A concrete example of such piling heretofore devised embraces I-beams for the simple sections and oppositely arranged, rigidly connected channel bars for the compound sections, the flanges of which are directed towards each other but separated a distance to receive the webs of the I-beams, with the flanges of said beams and bars interlocked with each other.

In the drawings:—Figure 1 is a fragmentary perspective view of the upper ends of the metal sheet piling arranged to constitute two meeting walls, showing my improved means for connecting the same. Fig. 2 is a partial plan view and a partial horizontal section thereof. Fig. 3 is a partial plan view and a partial horizontal section, showing a slight modification.

As shown in the drawings, 10, 10 designate the simple units and 11, 11 the compound units of the metal sheet piling. The said simple units comprise, as herein shown, I-beams, the oppositely extending marginal flanges 12, 12 of which have laterally interlocking and longitudinally sliding engagement with the compound units. The compound units each comprises two laterally separated, rigidly connected rolled shapes 14, 14 provided at their margins with right angle flanges 16, 17, the two flanges at each

edge of the compound units being directed toward each other, but terminating such distance apart as to receive between them the webs of the I-beam units, with the flanges 60 thereof interlocking with the flanges of the members of the compound units. Throughout the length of a wall composed of said units, except at the junction thereof with a transverse wall, the said members of the 65 compound units may consist of plain channel bars, or the units at the sides of said junctions may be otherwise formed or arranged for interlocking connection. One or both of the members of the compound unit located 70 at the junction of a main wall with a transverse wall is, however, of special form to constitute a junction connection, as will hereinafter appear.

In accordance with my invention, the junction of a main wall with a transverse meeting wall occurs in line with a compound unit of said main wall. One of the side members of the compound unit of a main wall at the junction thereof with a transverse wall is formed to provide on the outer side face of said member adjacent to the transverse wall with a vertical groove to receive the flanges 12 of the simple unit of the transverse meeting wall. If the main wall is to be joined with a transverse meeting wall at one side only, the compound junction unit of the main wall is provided at one side only with such vertical groove. 85 If, however, the main wall is to be joined to two oppositely extending transverse walls, then both members of the compound junction unit will be provided with said vertical grooves for interlocking connection with the 90 said simple units of the transverse walls. 95

As shown in Figs. 1 and 2, provision is made for connecting a transverse wall with one side only of the main wall. In this event one side or member of the compound junction unit of the main wall may consist of a plain channel bar 14. The other side or member of said junction unit is shown as consisting of an I-beam, two of the flanges 17, 17 of which are parallel with and directed towards the flanges 16, 16 of the channel bar 14. The opposite flanges 18, 18 of said I-beam member are bent or folded inwardly towards the web of said member so as to form between said web and the inwardly folded flanges grooves to receive the flanges 12 of the I-beam or simple unit of the transverse meeting wall. The said 100 105 110

groove thus formed affords guiding and locking engagement between the junction unit and the simple unit of the transverse meeting wall, permitting one unit to be guided from the other when being driven in the same manner as the simple and compound units of the usual construction are guided one from the other while being driven, and also affording means to interlock the junction units to the other units of the wall. The said lateral members of the compound units are fastened rigidly together by means of bolts 19, 19 extending transversely through the webs thereof, and spacing sleeves 20, 20 which surround said bolts and bear at their ends against the inner sides of the members of the compound units. Said spacing sleeves serve to space or hold the said members a fixed distance apart, and said members are held from spreading by the heads and nuts of said bolts. The bolts also serve to greatly strengthen the compound units. The heads of the bolts 19 are countersunk in the web of the I-beam member of said junction unit so as to afford a plain or non-projecting exterior face on the side of the unit adjacent to the transverse wall for engagement with the flanged margin of the adjacent simple or I-beam unit of such transverse wall, as shown in Fig. 2. The spacing sleeves 20 are located at such distance inwardly from the interlocking flanges of the members of the compound units as to constitute guides for engagement with the flanged margins of the simple units 10 to guide the units while being driven into place and to hold said units rigidly connected.

In the construction shown in Fig. 3, provision is made for joining two oppositely extending transverse walls to a single junction unit of the main wall. In this construction, the two members 25, 25 of the compound junction unit consist of I-beams, the inner flanges 26, 26 of which interlock with the flanges of the simple or I-beam units. The outer flanges 27, 27 of said I-beam members of the compound unit are folded inwardly towards the webs of said members to provide vertical grooves at both sides of said unit to receive the flanges of the simple or I-beam units. In the latter construction the two members of the compound junction unit are fastened together by rivets 28, 28, the heads of which are countersunk in the webs of said side members so as to provide plain or non-projecting surfaces on the exterior sides of the webs of said members for engagement with the flanged margins of the simple units 10.

It will be obvious that the junction of two meeting walls may occur at the corner of an inclosing wall made up of the metal piling described, or may occur at any point or points in the length of the wall.

A practical adaptation of the invention is found in the construction of cofferdam retaining walls, wherein such walls comprise parallel, inner and outer, separated wall members surrounding a central well or compartment, 70 and wherein the parallel wall members are joined by short connecting wall lengths to form between the wall members a series of pockets to be filled with a suitable packing for filling material to produce a water tight 75 wall as a whole. In such constructions, the walls herein shown, which embrace the junction units, may be regarded as the wall members, while the transverse walls may be regarded as the connecting members of the 80 wall structure.

The construction described affords an exceedingly simple and effective means of joining two meeting metal sheet piling walls and avoids the necessity of providing a special 85 junction fitting at the intersection of the walls as has heretofore been common in the use of sheet piling of the construction herein shown. Moreover, the junction of a meeting wall with the compound or stronger unit of 90 a main wall is advantageous inasmuch as it provides great strength and durability at the junction or meeting point. I have herein referred to one of the walls as a main wall for convenience of description only, and it 95 will be understood that either of two meeting walls thus joined may be regarded as the main wall.

I claim as my invention:—

1. In interlocking sheet metal piling, a 100 junction unit for joining a main wall to a transverse wall, said junction unit comprising two laterally separated members having at their margins flanges turned toward each other to interlock with flanges of adjacent 105 units of the main wall, one of the members of said unit having at its margins other flanges turned toward each other to interlock with the flanges of an adjacent unit of the transverse wall.

2. In interlocking metal sheet piling, a junction unit for joining two meeting walls at an angle comprising two laterally separated, rigidly connected side members provided at their margins with longitudinal 115 flanges which are directed towards but separated from each other, at least one of said members being provided at its margins with integral longitudinal flanges which are folded inwardly towards the outer side of the 120 web of said member to constitute between the same and said web a groove to receive the flanged margin of the unit of a transverse meeting wall.

3. In interlocking metal sheet piling, a 125 junction unit for joining two meeting walls at an angle comprising two laterally separated, rigidly connected side members provided at their margins with longitudinal flanges which are directed towards but sep- 130

arated from each other, at least one of said members comprising an I-beam, the flanges on one side of which are folded inwardly towards the web of said I-beam member to 5 constitute a longitudinal groove at the outer side of said unit.

4. In interlocking metal sheet piling, two walls meeting at an angle, said walls comprising alternate simple and compound units 10 which are flanged at their margins for interlocking engagement, and longitudinally sliding, interlocking engagement between the side of the compound unit of one of said walls and a simple unit of the other wall, 15 including flanges integral with one of the side members of the compound unit.

5. In interlocking metal sheet piling, two walls meeting at an angle, said walls comprising alternate simple and compound units 20 which are flanged at their margins for interlocking engagement, one of the compound units of one wall being formed at its side adjacent to the other wall with integral, in-

wardly turned flanges to provide a longitudinal groove to receive the flanged margin 25 of a simple unit of said latter wall.

6. In interlocking metal sheet piling, two walls meeting at an angle and a junction unit for uniting said walls, said junction unit comprising two members provided on two 30 remote sides of the unit with flanges adapted for interlocking connection with the adjacent units of the main wall and provided on its side between said remote sides with integral flanges adapted for guiding and locking 35 engagement with the adjacent unit of the meeting wall.

In testimony, that I claim the foregoing as my invention I affix my signature in the presence of two witnesses, this 24th day of 40 March A. D. 1908.

MANLEY W. CLUXTON.
